UNITED STATES PATENT OFFICE.

HENRY A. SIEBERT AND FREDERICK W. HODGES, OF DETROIT, MICHIGAN.

DESIGN FOR A RADIATOR-LOOP.

SPECIFICATION forming part of Design No. 26,247, dated November 3, 1896.

Application filed March 30, 1896. Serial No. 585,491. Term of patent 7 years.

To all whom it may concern:

Be it known that we, HENRY A. SIEBERT and FREDERICK W. HODGES, citizens of the United States, residing in the city of Detroit, 5 county of Wayne, State of Michigan, have invented and produced a new and original Design for Radiator-Loops, of which the following is a specification, reference being had to the accompanying drawing, which forms a 10 part thereof.

The design in its entirety is intended to be applied to the end loop of a stack of radiator-loops.

In the drawing the figure is an elevation 15 of the side of the end loop, showing the design in its entirety.

The design consists in raised figures on the curved surface of a radiator-loop that is nearly rectangular in outline, comprising a spray of 20 leaves and blossoms rising at either side from the base and extending upward about one-quarter or one-third of the distance to the top, and a similar spray extending down on either side from the top for about one-quarter or one-third of the distance. Between the two down-dropping sprays and the two rising sprays is a diamond-shaped panel, smooth and plain except for a panel of raised figures in its center. At the extreme top, at the front 25 and rear, are medallion-heads of cherubs, facing outward or away from the central line, and showing to one looking directly at the side a little more than the profile. Centrally at the top and between the two medallions 30 just described is a full-faced medallion of a lion's head. Twined around these medallions

and dropping from them are sprays of leaves and flowers. The central figure shows the medallion of a lion rampant, with vines and flowers twined around the body. At the bottom on each side, within the spray of vines and flowers, there is a fanciful head, and the ornamentation extends downward, covering the legs and extending to the extreme bottom part of the radiator-loop.

The medallion-heads at the top are indicated by the letters A', B, and C. The rampant lion in the center of the figure is indicated by the letter D, and the fanciful heads in the bottom are indicated by the letters E 45 and F.

The principal feature of this design consists in the light graceful sprays of leaves and flowers surrounding and drooping from the medallions at the upper part, and the light 50 graceful sprays of flowers and vines rising from the lower part, those above and those below both separating, so as to leave a plain surface of substantially diamond-shaped form having a central ornamental figure, and 55 a spray of vines and flowers entwining a rampant animal.

What we claim is--

The design for a radiator-loop, substantially as shown and described.

In testimony whereof we sign this specification in the presence of two witnesses.

HENRY A. SIEBERT.

FREDERICK W. HODGES.
